UNITED STATES PATENT OFFICE.

ARTHUR KING, OF CHICAGO, ILLINOIS.

ASPHALT-RIPPER.

No. 878,638.

Specification of Letters Patent.

Patented Feb. 11, 1908.

Application filed June 10, 1907. Serial No. 378,143.

To all whom it may concern:

Be it known that I, ARTHUR KING, a citizen of the United States, residing at Chicago, in the county of Cook and State of Illinois, 5 have invented certain new and useful Improvements in Asphalt-Rippers, of which the following is a full, clear, and exact description.

My invention relates to certain new and 10 useful improvements in asphalt rippers, the object being to provide a mechanically operated power device of this character for ripping up asphalt street paving. Usually this is done by manual labor, the asphalt being 15 cut or broken up into blocks and removed by pick axes or crow bars, and it is therefore a very laborious task, requiring a great number of men to a given piece of work and consequently being quite an expensive under- 20 taking. The asphalt layer itself, being of a very tough and tenacious character, it is exceedingly difficult to break up and separate the same from the concrete bed and my device has been designed to simplify the work 25 of ripping the asphalt layer from the bed of concrete, and the breaking up of the asphalt into small blocks.

The invention is fully described in the following specification, and shown in the accompanying drawing in which

Figure 1 is a side view of an ordinary street paving roller, with the ripper bar attached thereto, and showing the parts in operative position, and Fig. 2 is a perspective view of 35 the ripper bar and a fragment of the rear end of a roller.

In these views 10, represents an ordinary street paving roller, traction engine or any other powerful self-propelled vehicle, which 40 is provided with a draw head 11, by which wagons or other wheeled devices may be coupled to the roller, traction engine, etc. The ripper bar is seen at 20, and is preferably in the form of a channel iron, having a web 45 member 21 and side flanges 22 that form reinforcements for the web 21. The upper ends of the flanges are cut away to form shoulders 23, which are adapted to bear against the drawhead, and the web 21, is 50 perforated at 24, for the coupling pin 12, which connects the ripper bar with the draw- head 11. The ripper bar is bent into the form of a reverse curve so as to leave an ap- proximately horizontal upper end 25, and in- 55 clin'd portion 26, and a slightly upturned

lower end or point 27. The lower end rests or rides upon a heel 28, which is rounded off, the edge 29, being raised slightly above the ground, the object of which is to allow the bar to rock upon its heel as a fulcrum, in the 60 operation of the device. The bar fits loosely in the drawhead so that it may adjust itself to the unevenness of the road, and may be handled by the attendant with greater ease in inserting it under the asphalt layer. A 65 plate 30, is usually secured upon the rear end of the roller immediately above the draw- head to protect the machine from injury.

Fig. 2 shows a steam roller that is provided with a double drawhead 12', 12'', the ripper bar being secured in the upper drawhead. I find that in ripping up asphalt of about one and one half to two or three inches in thickness the point 29 should normally be raised about three quarters of an inch from the 75 ground but that when asphalt of less thickness is to be removed the point should be held nearer the ground. By raising or lower- 80 ing the upper end of the ripper bar the varia- tion at the lower end can be easily affected, it 85 being only necessary to withdraw the coupling pin, insert the ripper bar in the proper draw- head and insert the pin.

In operation, the ripper bar is coupled to the steam roller, and the latter run or rather 85 backed over the pavement from which it is desired to remove the asphalt layer. An attendant directs the point underneath the edge of the asphalt, preferably by prying it up or by placing the point of his pick ax 90 under the edge of the asphalt layer, and de- deflecting the point of the ripper bar under- 95 neath the same. The operator of the roller then backs up his machine causing the ripper bar to slide underneath the asphalt layer and bodily raise up the asphalt slab which lies in its path by means of the inclined portion of the ripper bar. When the raised block or slab has been raised sufficiently it breaks 100 away from the body of the asphalt and slides up and falls off the bar onto the road. Much of the broken asphalt falls into the path of the steam roller and the rollers thereof run over this collection of broken up portions, causing considerable jar to the machine, 105 which has the effect of vibrating the ripper bar so as to cause a prying action to its free end, thereby more effectually loosening the asphalt layer from the concrete bed. The slight incline of the flanges at the point makes 110

the insertion of the point comparatively easy and the more abrupt inclined portion breaks the slabs away from the main body of the asphalt layer.

- 5 By this machine I have been enabled to save an enormous amount of expense and labor in ripping up asphalt paving and at the same time have accomplished the same amount of work in very much less time. In 10 experimenting with various devices I have found that it is practically impossible to use a device which is pulled along the pavement, because the asphalt blocks slide up and engage the draft beam, thereby raising the 15 cutting or ripping point up and away from the pavement. For this reason I have found it desirable and more effectual to attach the ripper bar to the rear end of the engine and push the same through the mass.
- 20 I am aware that various alterations and modifications of this device are possible without departing from the spirit of my invention, and I do not therefore desire to limit myself to the exact construction shown and described 25 in this specification.

I claim as new and desire to secure by Letters Patent:

1. In an asphalt ripper, a ripper bar constructed and arranged to be secured to a suitable power device said ripper bar having an unobstructed breaking surface from end to end.
2. In an asphalt ripper, a ripper bar having an inclined breaking portion, upon and by which the slabs of asphalt, that lie in the path of the bar, are bodily raised and broken away from the mass, a heel and an upwardly inclined point, riding upon the heel of the ripping bar.
3. In an asphalt ripper, a ripper bar having a portion arranged to be coupled to a power device, a downwardly inclined reinforced breaking portion and a forwardly extending point.
4. In an asphalt ripper, a ripper bar comprising a channel iron bent into a reverse curve, one end of which is arranged to be connected to a steam roller, or other power device, and the other end of which is ar-

ranged to slide in between the asphalt layer 50 and the bed of concrete.

5. In an asphalt ripper, a ripper bar having suitable ripping edges, which have between them an unobstructed portion, extending from end to end of the bar, and means for forcing said ripper bar through the material to be acted upon.

6. In an asphalt ripper, a ripper bar having a suitable ripping edge, means for vibrating and forcing said ripper bar through the material to be acted upon and a loose pivot connection between said means and the bar.

7. In an asphalt ripper, a ripper bar having an upwardly inclined point, a riding heel an inclined breaking portion arranged to bodily raise and break the slabs of asphalt, which lie in the path of the bar, from the mass, and means for pushing said ripper bar through the material to be acted upon.

8. In an asphalt ripper, a ripper bar having an upwardly inclined point, a riding heel an inclined breaking portion arranged to bodily raise and break the slabs of asphalt, which lie in the path of the bar, from the mass, and means for vibrating the ripper 75 bar upon its heel as a fulcrum and pushing said ripper bar through the material to be acted upon.

9. In an asphalt ripper, an inclined ripper bar, having a ripping edge, and a riding heel, and a power device, having a suitable draw head for coupling the ripper bar to the power device, said bar being coupled to one end of the power device so as to be pushed thereby and in front of the same.

85 10. In an asphalt ripper, a ripper bar, having a ripping edge, and a riding heel, a power device a plurality of vertically arranged drawheads, and means for loosely coupling the ripper bar to the power device and in front thereof, whereby the position of the inclined point may be altered with respect to the bed.

ARTHUR KING.
